VAGINAL II

Application filed April 6, 1

This invention relates to vaginal douches or irrigators; and aims to provide a device of this character that is of simple, economical and sanitary construction, and that consists of a minimum number of parts that may be readily detached or reassembled, that is resistant to rough usage and not easily broken, that may be easily and thoroughly cleansed, and that possesses further and other advantages that will be better apparent from the following description of a preferred embodiment of the invention.

In the accompanying drawings forming part of this specification, in which like numbers of reference denote like parts wherever they occur,

Figure 1 is a view of the anterior or insertible end of the device;

Figure 2 is an axial sectional view, taken 20 on the line 2-2 in Figure 1;

Figure 3 is a transverse sectional view, taken on the line 3-3 in Figure 2; and

Figure 4 is an elevation of the device.

The irrigator comprises a thin tubular 25 metal shell 1, preferably of drawn or wrought aluminum, creased or grooved interiorly intermediary of its ends to form an exterior annular flange 2, and preferably convexly converging at its anterior end, as at 3, to form 30 a reduced opening thereat. That portion 4 of the shell disposed anteriorly of the flange 2 is depressed at intervals around its periphery to define a series of parallel longitudinal channels 5, there being, finally extending 35 in the present embodiment, four of them, that are slotted longitudinally, preferably about half the length of the channels, the slots or openings 6 being disposed in the upper and lower ends, respectively, of alternate channels. The depression of the slotted portion 40 prevents the membrane of the vagina from being entrained by the slots, and, furthermore, provides grooves for conveying the fluid in the vagina into the slotted perforations 6.

The cylindrical posterior end 7 of the shell 1 fits into a recess 8 in the anteriorly presented face 9 of a metal base 10, preferably substantially elliptical contour. The base 50 10 is preferably an aluminum casting having

therewith the effluent and in- 11 and 12, respectively, that s posterior side 13, and are passages 14 and 15, respec- 55 n into the inner face 9 of the e recess 8 or the confines of

g 16, preferably, also, of 60 provided with a convex head closes the converging anterior shell 1, so that the outer config- 65 ead 17 is substantially a con- configuration of the convex of the shell 1. The head 17 an annular shoulder 18 that 70 ie anterior end of the shell 1 is the head from a reduced 75 tion 19 that projects into the the shell 1. The head or tip d to provide a plurality of 70 rough which fluid in the in- 75 ie neck 19 may be discharged a spray into the vagina.

22, preferably, also, of alumi- 75 posite ends in screw-threaded 80 the interior of the neck 19 of 85 16 and the influent passage respectively, said tube func- 90 t communication between the 95 and the passage 15 and, also, 100 shoulder 18 of the tip 16 and the recess 8 of the plate or base 11, thereby forming closures 85

sheath 23 of rubber or other 90 durable material preferably inti- 95 mately fits the anterior 95 of the base 10, and the inner 100 25 of the pad is substantially 100 a configuration to the con- the vulva, so as to inti- latter and effectively close 100

the entrance to the vagina. A flexible tube or hose has one end connected to a suitable source of irrigating fluid or running water, and the other end connected to the nipple 12. The fluid passes through passage 15 and tube 22 into nozzle-head or spray-tip 16 and is sprayed against the membrane of the vagina, from whence it is drawn through elongated apertures 6 into the shell 1 and educted through duct 14 into a suitable flexible tube or hose connected to the nipple 11, and from thence conveyed to a suitable point of discharge.

It will be observed that the device comprises only five parts and may be readily taken apart by simply unscrewing the tip 16 and the tube 22, after which the shell 1, base 10, and pad 23 may be easily pulled apart. The parts in contact with the irrigating fluid, being of aluminum, are not easily corroded and are easily cleansed. The parts are simple and are adapted to be economically manufactured. Moreover, being of metal and soft rubber, they are not easily broken as often occurs when irrigators of fragile material, such as hard rubber, are dropped on the hard tile floor of a bathroom or are subjected to other rough usage.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. In a vaginal irrigator, a tubular shell of drawn metal provided with an annular exterior flange intermediary of its ends and with lateral openings intermediary of said flange and one of said ends, a metal spray-tip forming a closure for the last-mentioned end of said shell, a metal base forming a closure for the other end of the shell and having influent and effluent ducts that open into the inner face of the base within the confines of the shell, a vulva-fitting pad of yieldable material intimately surrounding said shell intermediary of said flange and said base and a metal tube within the shell having its opposite ends in screw-threaded connection with the spray-tip and the influent duct of the base, respectively, said tube functioning to compress said pad between said flange and said base as well as effecting communication between said tip and said influent duct.

2. In a vaginal irrigator, a tubular shell having a series of parallel longitudinally extending channels having slots disposed in the bottoms thereof, an annular exterior flange arranged intermediate the ends of said shell, a base forming a closure for one end of the shell and having exteriorly projecting influent and effluent nipples provided with

passages that open into the inner faces of the base within the confines of said shell, a perforated spray-tip forming a closure for the other end of said shell, a vulva-fitting pad intimately surrounding said shell intermediary of said flange and said base and a metal tube within the shell having its opposite ends in screw-threaded connection with the spray-tip and the influent duct of the base, respectively, said tube functioning to compress said pad between said flange and said base as well as effecting communication between said tip and said influent tube.

In testimony whereof I hereunto affix my signature.

ROLLA C. LAWRY.
